UNITED STATES PATENT OFFICE.

ADELBERT O. BENECKE, OF NEWARK, NEW JERSEY, ASSIGNOR TO AMERICAN INSTRUMENT COMPANY, OF NEWARK, NEW JERSEY, A CORPORATION OF NEW JERSEY.

ELECTRICAL RESISTANCE MATERIAL.

No. 839,257.

Specification of Letters Patent.

Patented Dec. 25, 1906.

Application filed January 5, 1906. Serial No. 294,709.

To all whom it may concern:

Be it known that I, ADELBERT O. BENECKE, of the city of Newark, county of Essex, and State of New Jersey, have invented a new and useful Improvement in Electrical Resistance Material, of which the following is a description.

Hitherto resistance devices for the general purpose to which my invention is adapted were constructed of rectangular strips of mica or asbestos, around which the resistance-wire is spirally wound and secured in convenient manner at the ends of such strips. The difficulty with such a construction is principally in the limited resistance capacity of such strips and their incapability of conforming to the shape of the various instruments in which they are used.

The object of my invention is to provide a continuous metallic strip of any length covered with insulating material and spirally wound with a resistance-wire and the whole thereafter covered with insulating material, so that the process of manufacture may be continuous and the product may be of any desired length and capable of being bent in any shape or coiled in spirals to suit any purpose for which it may be adapted.

In the accompanying drawings, forming a part of this specification, Figure 1 represents a section of a resistance-strip, illustrating the various steps in the process of manufacture. Fig. 2 illustrates one form, and Fig. 3 still another form, which the completed product may take. Fig. 4 illustrates a portion of the end of a strip, showing the method of attaching the leading-out and the leading-in contact. Fig. 5 is a cross-section on line $x-x$ of Fig. 4. Fig. 6 illustrates another form of end connection. Fig. 7 illustrates a modified form of resistance-strip, and Fig. 8 illustrates another modified form.

The metal base-strip A may be of any length desired or convenient to manipulate, which metallic ribbon or strip A, I cover with a spirally-wound ribbon B, of paper, silk, or other suitable insulating material. I may cover this paper, &c., after it has been applied to the strip A with a coat of varnish; but in many cases I find this to be unnecessary. Upon the ribbon or strip as thus insulated I wind the resistance-wire C, as shown, continuously throughout the length

of the strip and thereafter cover the same with the spirally-wound strip of paper, silk, or other suitable insulating or protective material D. A long strip or coil thus constructed may be kept in stock and short lengths cut off, as desired, for any purpose for which the same may be used.

In Fig. 4 I have shown a means of attaching a leading-out contact. This is done by punching the apertures E' through the end of the strip, first removing a portion of the protecting strip of material D and the wire C for some distance. After punching, the strip D is restored to cover the apertures, and thereafter the flexible strip or contact-piece E is lapped around the end and compressed into the apertures, as shown in Fig. 5. The end of the wire C is then lapped upon the contact-piece E and soldered or otherwise secured thereto at C', after which the covering B may be restored as far as may be deemed necessary in order to properly protect the convolutions of the wire C. The structure of Fig. 6 is substantially the same as that described in connection with Figs. 4 and 5, the exception being that the contact-piece E' projects longitudinally of the strip, while the contact-piece E projects laterally. I am able to produce practically the same results by coating the metal strip A' with varnish, over which the convolutions of the wire C' lie, and thereafter I cover the wire with the coat of varnish D', as illustrated in Fig. 7. In this manner I am able to produce a continuous metallic strip of any length to give the necessary required resistance and to fold, coil, or bend the same in any desired manner to fit the instrument in which the resistance-strip may be used. This resistance material possesses the added advantage of conducting away or absorbing the heat generated in the wire C, because of the relatively large mass of metal in the strip A.

A resistance-strip constructed along the lines I have indicated possesses not only the characteristics above noted, but has, in addition, the advantages of non-inductivity and very small capacity, which advantages will be readily recognized by those skilled in the art to which my invention pertains.

In each of the several forms of my invention the wire C may be either bare or covered, and in case I use the ribbon I may use

covered or insulated wire to provide the necessary insulation between the wire itself and the metallic base strip or ribbon, as shown in Fig. 8. Where such covered wire is used, it is not necessary to use the protective strip D, although I prefer to use such strip or covering as a safeguard against accidental abrasion of the insulating-covering of the wire and the almost inevitable contact of successive convolutions and consequent short-circuiting of the resistance-wire.

In Figs. 4, 5, and 6 I have shown the contact-strips E as secured to the ends of the resistance-strip, with the wire C soldered to the contact-piece. Inasmuch as this contact-piece E is insulated from the base strip or ribbon A in case of the use of metallic base or ribbon, I may connect the other end of the wire to said base and use the end thereof for direct external connection.

What I claim is—

1. An electrical resistance material composed of a continuous flexible metallic strip or ribbon, an insulating-covering for said strip or ribbon and a resistance-wire, spirally wound upon said strip or ribbon throughout its length.
2. An electrical resistance material composed of a continuous flexible metallic ribbon, and insulating-covering for said metallic ribbon, a high-resistance wire spirally wound upon said covering and a protective covering outside of said spirally-wound wire.
3. An electrical resistance material composed of a continuous flexible metallic strip or ribbon, a high-resistance wire spirally wound upon and insulated from said strip or

ribbon throughout its length and insulating material covering said spirally-wound wire.

4. An electrical resistance material composed of a long flexible metallic ribbon, an insulating-covering for said ribbon, a high-resistance wire spirally wound upon said covering throughout the length of the ribbon, and an insulating-covering for the whole.

5. An electrical resistance material composed of a long ribbon of metal, a ribbon of insulating material spirally wound upon said metal ribbon to form an insulating-cover therefor, a high-resistance wire spirally wound upon said insulating-cover throughout the length of said metal ribbon.

6. An electrical resistance device, consisting of a strip or ribbon of flexible metal, a high-resistance wire spirally wound upon and insulated from said ribbon and a leading-out contact secured to the end of said ribbon, said contact being directly connected with one end of said resistance-wire.

7. An electrical resistance device, consisting of an insulated flexible metallic strip or ribbon, a high-resistance wire spirally wound upon said strip or ribbon, a protective covering for said resistance and leading-out contacts secured upon the ends of said ribbon, said contacts being directly connected with said wire and insulated from said metallic ribbon.

This specification signed and witnessed this 2d day of January, 1906.

ADELBERT O. BENECKE.
